UNITED STATES PATENT OFFICE.

GEORGE W. CONOVER, OF CHICAGO, ILLINOIS.

DISH-WASHING MACHINE.

1,365,382.

Specification of Letters Patent. Patented Jan. 11, 1921.

Application filed March 5, 1919. Serial No. 280,719.

To all whom it may concern:

Be it known that I, GEORGE W. CONOVER, a citizen of the United States, residing at Chicago, in the county of Cook and State 5 of Illinois, have invented a new and useful Improvement in Dish-Washing Machines, of which the following is a specification.

This invention relates particularly to machines adapted to the purpose of washing 10 dishes.

The primary object is to provide a machine of simple construction and moderate cost, which is thoroughly adapted to the purpose indicated.

15 The invention is illustrated in its preferred embodiment in the accompanying drawing, in which—

Figure 1 represents a broken vertical sectional view of a dish-washing machine constructed in accordance with the invention; Fig. 2, a broken sectional view taken as indicated at line 2 of Fig. 1; and Fig. 3, a broken horizontal sectional view taken as indicated at line 3 of Fig. 1.

20 In the embodiment of the invention illustrated, A represents a can, or vessel, which affords a washing chamber, said vessel being provided with a removable top A'; B, a cast-iron spider upon which the vessel A is mounted, and which affords a reinforcement for the bottom of the vessel, and affords, also, bearings for various operating parts; B', a frame, or standards, upon which the spider B is rigidly mounted; C, 25 a shaft journaled in the hub-portion of the spider B and having its upper portion projecting into the lower portion of the vessel A; D, a water-propelling device, or paddle, demountably secured to the upper end of 30 the shaft C; and E, actuating mechanism for the propeller shaft C.

The vessel A may be conveniently formed 35 of sheet-metal, and preferably has its cylindrical vertical wall provided with vertical corrugations 1, which co-act with the propeller D to cause the water to be thrown in sheets, or sprays, over and through the 40 dishes, which may be supported in the vessel A by any suitable means, as, for instance, by the open-work tray, or basket, F. The 45 vertical wall of the vessel is preferably provided, also, with a lower inwardly-struck circumferential bead 2, which is located some distance above the dished bottom 3 of the vessel. Also, the vertical wall of the 50 vessel is preferably provided with inwardly-

struck circumferential beads 4 and 5, which are spaced some distance apart and located some distance above the reinforced upper edge 6 of the vertical wall. 60

The top, or cover, A', preferably comprises an upwardly dished sheet-metal member provided centrally with a handle 7, and equipped at its circumference with a reinforcement 8 and a series of spring-arms, 65 or supports, 9, which are adapted to engage the lower bead 4 when the top is in the closed position, and are adapted to engage the bead 5 when the top is lifted somewhat above the upper edge 6 of the vessel, so as to 70 provide a ventilating space between the cover and the vessel.

The spider B comprises a hub 10, radial arms 11, and a flat ring 12, carried by said radial arms. One of the arms 11 has a de- 75 pressed bearing, or support, 13, which carries a vertical pivot for one of the members of the actuating mechanism E; and at one point the ring 12 has formed integrally therewith an upwardly-projecting lug, or 80 support 14, which serves to carry the pivot of the actuating lever of the mechanism E. The hub 10 of the spider is provided with a perforation, through which extends a gland-like bearing 15 for the shaft C. The 85 member 15 has its lower end equipped with a flange 15^a which is secured, by cap-screws 16, to the hub 10, against the lower surface of which the flange 15^a bears. The sleeve, or bearing, 15, extends through the hub 10 90 and through a central perforation in the bottom 3 of the vessel A, the upper end of the sleeve being externally threaded.

The upper end of the shaft C is journaled in a sleeve 17 which has an enlarged 95 lower end, which is internally threaded and screwed on to the upper end of the sleeve 15, a washer, or gasket 18, being interposed between the lower end of the sleeve 17 and the bottom 3 of the vessel A. 100

It will be understood that the perforate central portion of the bottom 3 of the vessel A is clamped between the hub of the spider and the lower end of the sleeve 17, a watertight joint being afforded. The upper end 105 of the shaft C is fitted with a cap, or bearing, 19, which is rigidly secured to the shaft and which rotates therewith, it being understood that the sleeve 17 remains stationary, the sleeve 17, being, in effect, an upward extension of the bearing afforded by the sleeve 15. 110 The cap 19 preferably has a depending

flange 19^a which fits freely over the upper end of the sleeve 17. The upper end of the shaft C is slightly reduced and fits into an angular opening in the bearing-cap 19. The bearing-cap 19 is secured in place by means of a cap-screw 20 and a washer 21, the cap-screw extending into a threaded socket with which the upper end of the shaft C is provided.

10. The propeller-blade, or paddle, D, is equipped at its inner end with an attaching arm, or bracket, 22, which is fixedly secured to and depends from the bearing-cap 19, and which may be integrally formed therewith. 15. if desired. Thus, the blade D will rotate with the shaft C, to which the paddle-supporting cap 19 is firmly secured.

The vertical corrugations 1 of the vessel A extend from the lower bead 2 approximately to the lower one 4 of the top beads. Thus, the vessel is well stiffened. The paddle D is disposed below the plane of the lower circumferential bead 2.

The mechanism E comprises a hand-lever 23 supported on a horizontal pivot 24 carried by the supporting lug 14 of the spider, the hand-lever being equipped at its lower end with a gear-segment 23^a; a lever 25 journaled on a vertical pivot 26 carried by the 30 supporting member 13 of the spider, the outer end of the lever being equipped with a gear-segment 25^a which engages the gear-segment 23^a, and the inner end of the lever being equipped with a gear-segment 25^b; 35 and a pinion 27 secured on the shaft C and meshing with the gear-segment 25^b.

The gear-segments 23^a and 25^a are covered by a guard 28, which depends from an extension of the stud 24 which forms the 40 pivot for the lever 23.

In operation, the oscillation of the hand-lever 23 serves to oscillate the lever 25, the motion being communicated through the pinion 27 to the vertical propeller shaft C. 45 The movement of the propeller D tends to create a centrifugal flow of the water which is contained in the lower portion of the vessel A, the water being forced upwardly over the lower circumferential bead 2 and along 50 the inner sides of the vessel. The internal circumferential bead 2 and the vertical corrugations of the vessel cause the water to be thrown in a spray over the dishes contained in the basket F, it being noted that 55 the bottom 29 of the basket is disposed slightly above the bead 2, the basket being provided with feet 29^a, which are supported upon the peripheral portion of the bottom of the vessel. Any suitable means for draining 60 the vessel (not shown) may be provided. When the machine is not in use, the cover A' is left in the elevated position, with the spring-supports 9 engaging the upper bead 5; so that the vessel A will be thoroughly 65 ventilated. It may be added that when the

machine is in use, the lower circumferential bead, 2, will aid in causing some of the water to break inwardly and strike the lower sides, or lower edge-portions, of the dishes.

The machine described is simple and cheap 70 in construction, easily operated, readily kept in sanitary condition, and highly effective in operation. The construction provides a water-tight connection between the bearing for the propeller-shaft C and the bottom of 75 the sheet-metal vessel, and also provides for a water-tight bearing for the shaft C, it being noted that, in practice, the normal water level of the water used for washing or rinsing purposes will be below the upper end of 80 the bearing-sleeve 17.

The advantages noted above are important, contributing as they do to the production of a machine which can be sold at a popular price and used in the household, as well 85 as in restaurants, or the like, where dishes must be washed in large numbers.

The foregoing detailed description has been given for clearness of understanding only, and no unnecessary limitations should 90 be understood therefrom, but the appended claims should be construed as broadly as permissible in view of the prior art.

What I regard as new, and desire to secure by Letters Patent, is:

1. In a dish-washing machine, the combination of a sheet-metal vessel having a bottom wall provided with a perforation, a spider supporting the bottom of said vessel and having a perforate hub registering with 100 the perforation of said vessel, a bearing sleeve extending through said perforations and having an elongated extension projecting a considerable distance above said bottom, a liquid tight joint being provided between said sleeve and the bottom of the vessel, a propeller shaft extending through said bearing-sleeve and projecting beyond the upper end thereof, means connected with the lower end of said shaft for actuating the 105 same, a bearing-member secured to the upper end of said shaft and engaging the extension of said bearing-sleeve, and a water-propelling blade supported by said last-named member.

2. In a dish-washing machine, the combination of a sheet-metal vessel having a bottom wall provided with a perforation, a spider supporting the bottom of said vessel and having a perforate hub registering with 120 the perforation of said vessel, a bearing sleeve extending through said perforations and having an elongated extension projecting a considerable distance above said bottom, a liquid tight joint being provided between said sleeve and the bottom of the vessel, a propeller shaft extending through said bearing-sleeve and projecting beyond the upper end thereof, means connected with the lower end of said shaft for actuating the 125 130

same, a bearing-member secured to the upper end of said shaft and engaging the extension of said bearing-sleeve, and a water-propelling blade projecting radially from 5 the extension of said bearing-sleeve and having connections at its inner upper portion with said last-named bearing-member.

3. In a dish-washing machine, the combination of a sheet-metal vessel having a bottom 10 provided with a perforation, a spider supporting said vessel and having a hub provided with a perforation, a bearing-sleeve extending through said hub and through the perforation in the bottom of said vessel and 15 having a threaded upper end, another bearing-sleeve having threaded connection with the upper end of said first-named bearing-sleeve and forming an extension of the bearing, the bottom of the vessel being clamped 20 between said members by means of the screw connections mentioned, a shaft extending through said bearing-sleeve and equipped at its upper end with a bearing-member, a propeller-blade carried by said bearing-member,

and actuating mechanism connected with the 25 lower end of said shaft.

4. In a dish-washing machine, the combination of a sheet-metal vessel having its bottom provided with a central perforation, a spider supporting said vessel having a hub 30 provided with a perforation, a gland-like sleeve extending through said perforations and having at its lower end an external flange secured to said hub, the upper end of said sleeve extending above the bottom of 35 the vessel and having a thread thereon, an upper bearing-sleeve having an enlarged lower end provided with a thread engaging said first-named thread, the lower end of 40 said last-named sleeve serving as a clamping means for the bottom of said vessel, a shaft extending through said sleeves and equipped at its upper end with a bearing-member, a propeller carried by said bearing-member, and actuating means connected 45 with the lower end of said shaft.

GEORGE W. CONOVER.
